UNITED STATES PATENT OFFICE.

OLIVER A. SMITH, OF SPRINGFIELD, MASSACHUSETTS.

DESIGN FOR A VEGETABLE-KNIFE.

42,194.

Specification for Design.

Patented Feb. 20, 1912.

Application filed November 18, 1911. Serial No. 661,178. Term of patent 7 years.

To all whom it may concern:

Be it known that I, OLIVER A. SMITH, residing at Springfield, in the county of Hampden and State of Massachusetts, and whose post-office address is box 101, have invented a new, original, and ornamental Design for Vegetable-Knives, of which the following is a specification, reference being had to the accompanying drawings, forming part thereof.

The figure is a side elevation of a vegetable knife showing my new design.

I claim:—

The ornamental design of a vegetable knife as shown.

OLIVER A. SMITH.

Witnesses:

MARGARET F. MCKENNA,
JAMES F. WALLS, Jr.
